CLAIM

The ornamental design for a blade configuration, as shown and described.

DESCRIPTION

FIG. 1 is a left-side perspective view of a blade configuration showing my new design;

FIG. 2 is a left-side elevational view of the design shown in FIG. 1;

FIG. 3 is right-side elevational view of the design shown in FIG. 1;

FIG. 4 is a front elevational view of the design shown in FIG. 1;

FIG. 5 is a rear elevational view of the design shown in FIG. 1;

FIG. 6 is a top plan view of the design shown in FIG. 1; and, FIG. 7 is a bottom plan view of the design shown in FIG. 1. The broken line showing of the knife is for purposes of environment and forms no part of the claimed design.
